PEGLESS LINE FOR SUSPENDING CLOTHES
AND FABRICS FOR DRYING OR DISPLAYKathleen Marguerite Varvel, South Yarra, near
Melbourne, AustraliaApplication May 19, 1944, Serial No. 536,238
In Australia May 22, 1943

4 Claims. (Cl. 211—119.14)

This invention relates to an improved flexible line comprising a series of interconnected wire links adapted to be longitudinally aligned when stretched horizontally between posts and other structures and each having means for firmly gripping wearing apparel, fabrics and like articles which are required to be suspended. The invention is intended principally for use as a gripping line for the suspension of clothes and fabrics to be dried, dispensing with the requirement of clothes pegs or pins, and it is further applicable as a line for gripping articles to be suspended for display in shop windows or fronts and other places in business establishments.

A turnable connection is provided between each link and adjacent links of the line so that the links will be longitudinally aligned when stretched horizontally and the opposite ends of the line are readily detachable from the posts or other fixtures between which it is stretched, whereupon it can be conveniently folded into small compass for carriage or, alternatively, for storage when it is not required for immediate use.

The principal object of the invention is to provide an improved flexible line consisting of a series of interconnected wire links of a construction which enables articles to be simultaneously gripped at opposite sides of the longitudinal centre line of each link of the series. By this means increased gripping surfaces are provided with corresponding enlargement of the capacity of the line for the suspension of clothes and fabrics which is a desideratum with devices of this character, more especially when used in residential flats and other places having limited room space.

Reference is made to the accompanying drawing, wherein:

Figs. 1 and 2 are views in side elevation and in plan, respectively, showing a wire link and portions of adjacent links of the series to which it is turnably connected.

Fig. 3 illustrates in side elevation a series of interconnected links of the line with fabrics suspended therefrom.

Each of the interconnected links of the flexible line is composed of two plain, untwisted wires of springy nature. The main wire is bent to provide two longitudinal gripping members 2 and 3 which are in parallel spaced relationship and terminate in enlarged eyes 4 and 5 having rounded portions 6, members 7 inclined to the horizontal, and curved parts 8. The gripping members 2 and 3 are spaced apart sufficiently to accommodate between them the second wire 9 which is positioned

longitudinally and extends diametrically across the eyes 4 and 5 thereby partitioning the same into upper and lower sections 10 and 11, respectively.

5 The two wires composing the link are fixedly secured together by spot-welding at the points indicated by 12. Secured by spot-welding to the outer end portions of the eyes 4 and 5 are rings 13 which are connected to similar rings on the adjacent links to thereby provide a turnable connection between all links of the series.

In use, corners or ends of clothes, fabrics or other articles to be suspended for the purpose of being dried or displayed are inserted through the 15 members 10 or 11 of the eyes 4 and 5 and are then slid laterally of said eyes whereby they are gripped between the longitudinal members 2 or 3 and the longitudinal dividing wire 9. The rounded and curved portions 6 and 8 of the eyes prevent the corners or ends of the clothes or fabrics being torn or otherwise damaged and the 20 inclined portions 7 of said eyes provide lead-in members which facilitate the insertion of the corners or ends of the clothes or fabrics between the gripping surfaces of the closely positioned wires 2—9 and 3—9 on the opposite sides of the longitudinal centre line of the link.

The links of the device are cadmium plated, or otherwise coated to prevent rusting.

30 What I do claim is:

1. A gripping line for the purposes described consisting of a series of interconnected wire links adapted to be longitudinally aligned when stretched between two posts or structures, each 35 of said links consisting of two wires secured to each other, one of said wires being formed with intermediate longitudinal parallel gripping members terminating in an enlarged eye at each end, and the other of said wires being positioned longitudinally between said gripping members and passing diametrically across said eyes, and rings secured to said eyes connected to similar rings of adjacent links to thereby provide a turnable connection between the series of links.

45 2. A gripping line for the purposes described consisting of a series of interconnected wire links adapted to be longitudinally aligned when stretched between two posts or structures, each 50 of said links consisting of two wires, one of said wires being formed with intermediate longitudinal parallel gripping members terminating in an enlarged eye at each end, and the other of said wires being positioned longitudinally between said gripping members secured to the same and passing diametrically across said eyes, and rings

secured to said eyes connected to similar rings of adjacent links to thereby provide a turnable connection between the series of links.

3. A gripping line for the purposes described consisting of a series of interconnected wire links adapted to be longitudinally aligned when stretched between two posts or structures, each of said links consisting of two wires, one of said wires being formed with intermediate longitudinal parallel gripping members terminating in an enlarged eye at each end, and the other of said wires being positioned longitudinally between said gripping members and passing diametrically across said eyes, and being secured at its ends to said eyes, and rings secured to said eyes connected to similar rings of adjacent links to thereby provide a turnable connection between the series of links.

4. A gripping line for the purposes described consisting of a series of interconnected wire links adapted to be longitudinally aligned when stretched between two posts or structures, each of said links consisting of two wires, one of said wires being formed with intermediate longitudinal parallel gripping members terminating in an enlarged eye at each end, and the other of said wires being positioned longitudinally between said gripping members secured to the same and passing diametrically across said eyes, and being secured at its ends to said eyes, and rings secured to said eyes connected to similar rings of adjacent links to thereby provide a turnable connection between the series of links.

KATHLEEN MARGUERITE VARVEL.
